UNITED STATES PATENT OFFICE.

PAUL B. LUM, OF WASHINGTON, DISTRICT OF COLUMBIA, ASSIGNOR TO WASHINGTON AUTOMOTIVE TRADE ASSOCIATION, OF WASHINGTON, DISTRICT OF COLUMBIA, AN ASSOCIATION OF THE DISTRICT OF COLUMBIA.

DESIGN FOR SIGN OR SIMILAR ARTICLE.

Application filed December 29, 1922. Serial No. 4,748. Term of patent 14 years.

To all whom it may concern:

Be it known that I, PAUL B. LUM, a citizen of the United States, residing at Washington, in the District of Columbia, have invented a new, original, and ornamental Design for Sign or Similar Article, of which the following is a specification, reference be-

ing had to the accompanying drawing, forming part thereof, in which the design is shown in elevation.

I claim:—

The ornamental design for sign or similar article, as shown.

PAUL B. LUM.
